UNITED STATES PATENT OFFICE.

EDWARD J. QUIGLEY, OF NEW YORK, N. Y.

COMBINATION-GARMENT.

1,139,800.

Specification of Letters Patent.

Patented May 18, 1915.

Application filed October 19, 1914. Serial No. 867,280.

To all whom it may concern:

Be it known that I, EDWARD J. QUIGLEY, a citizen of the United States, and a resident of New York city, county and State of New York, have invented certain new and useful Improvements in Combination-Garments, of which the following is a specification.

This invention relates to combination garments and the objects of the invention are to make a combination garment that is easy to put on or take off and can be made either as underwear or as a shirt with drawers attached.

Further objects of the invention are to provide means for lengthening or shortening the garment.

To the accomplishment of the above objects and to such others as may hereinafter appear the invention comprises, a combination garment having shirt and drawers suitably united and open from the neck to crotch, and also open in front about the waist at right angles to the opening from the neck to the crotch.

The invention further comprises means about the waist and adjacent the waist opening for lengthening or shortening the garment.

In the drawings: Figure 1 is a front view of an undergarment showing one form of my invention. Fig. 2 is a front view of a dress shirt with drawers attached embodying my invention. Fig. 3 is a view similar to Fig. 1 showing the garment open. Fig. 4 is a front view of an undergarment similar to Fig. 1 showing means about the waist adjacent the waist opening for lengthening the garment. Fig. 5 is a view similar to Fig. 4 showing the garment lengthened. Fig. 6 is a front view of an undergarment showing different means for lengthening and shortening the garment. Fig. 7 is a detail sectional view taken on the line 7—7 of Fig. 4. Fig. 8 is a detail sectional view taken on the line 8—8 of Fig. 6.

Referring to the drawings, 1 designates the body of an undergarment; or union suit, to which is secured the drawers 2, in the present instance shown as of knee length, although the same may be made longer if so desired. The body 1 is open down the front from the neck to below the waist line as shown at 3, the drawers being open from the waist line to the crotch as shown at 4. The garment is also cut so as to be open

along the waist line, between the points 5 and 6, which are situated, in the present instance, approximately half way between the side of the garment and the central openings 3 and 4. The body of the garment is provided with extensions or aprons 7 which close the horizontal waist opening between the points 5 and 6, as clearly shown in Figs. 1 and 2. Suitable fastening means such as buttons 8 are provided for closing the garment.

From the above description it will be seen that the garment shown in Figs. 1 and 3 is open from the neck to the crotch and also open along the front part of the waist line. This cutting of the waist line, as just described, affords a certain amount of play, that is absolutely essential to a person that is stout. The provision of the aprons or extensions 7 insures the closing of the garment at the waist line. The garment also affords more room to get into and out of it than any other similar garment, the provision of the waist line opening permitting the garment to be more widely opened than would otherwise be the case, as clearly illustrated in Fig. 3. This large opening is practically essential in the case of a stout person and very convenient to even a slender person when the garment is being put on or taken off.

If desired the waist line opening can be made greater or less as desired, but I have found that the garment is more convenient when cut as shown in the drawings.

Fig. 2 shows the application of the invention to an outer shirt or dress shirt with drawers attached. The provision of the waist line opening with a dress shirt permits the stiff bosom of the shirt to be straightened out and retained in this position without undue tension in the crotch of the garment, and also permits the end of the bosom to move downward when the wearer is in a sitting position.

In order to adapt the garment to fit people of various heights and also to allow for shrinkage of the garment due to washing, the garment as shown in Fig. 4 is provided with one or more plaits 10 about the waist of the garment. The plaits 10 terminate at the ends of the transverse opening designated by the points 5 and 6, and when desired one or more of the plaits can be ripped to lengthen the garment. By referring to Fig. 5 it will be seen that one of the plaits 10 has been ripped or let down to

lengthen the garment. Fig. 7 shows in cross-section the arrangement of the plaits 10 taken on the line 7-7 of Fig. 4.

Instead of the plaits being sewn together as shown in Figs. 4, 5 and 7, the same may be buttoned together as shown in Fig. 6 by means of buttons 11. Fig. 8 shows in cross-section the arrangement of the plaits 10 buttoned together taken on the line 8-8 10 of Fig. 6. When the plaits are buttoned together the garment can readily be lengthened or shortened as desired. The plaits 10 it will be noticed do not extend across the front of the garment, but only extend to the edges 5 and 6 of the transverse opening leaving the bosom of the garment free from plaits which is a decided advantage especially when the garment is used without ripping the plaits. If the transverse opening 20 was not provided it would be necessary to extend the plaits across the bosom of the garment to the edges of the opening extending from the neck to the crotch, this construction would not only be objectionable as 25 providing plaits across the bosom of the garment, but the edges of the garment along the central opening would be very bulky where the plaits occurred, due to the doubling over the extra plies of cloth along the 30 edges of the central opening which would be hard to button and would also present an unfinished appearance.

From the above it will be seen that the transverse opening makes it possible to provide plaits for letting out the garment without extending the plaits entirely across the front making a neat appearing garment that can be lengthened or not as desired. The transverse opening also makes the garment 40 easy to put on and take off and also permits a certain amount of play in the front of the garment as the front of the drawers are preferably not buttoned to the front of the shirt.

45 The back opening is not shown as any suitable back can be used.

While the invention has been described with particular reference to the details of construction, the same is not to be considered as limited thereto as many changes can 50 be made and still fall within the scope of the invention set forth in the following claims.

What I claim is:

55 1. A combination garment comprising in a one piece suit, shirt and drawers, open from the neck to the crotch, and continuous

along the sides of the garment, but separated from each other for a portion of the front to each side of the center, whereby relative vertical movement of the shirt and drawers at said separated portion is permitted, and aprons on the front of said shirt extending below said separated portion. 60

2. A combination garment comprising in 65 a one piece suit, shirt and drawers, open from the neck to the crotch, and continuous along the sides of the garment, but separated from each other for a portion of the front to each side of the center at the waist-line, 70 whereby relative vertical movement of the shirt and drawers at said separated portion is permitted, and aprons on the front of said shirt extending below said separated portion. 75

3. A combination garment comprising a one piece suit consisting of shirt and drawers combined, the central portion of the front of the shirt extending downward to at least the waistline, the drawers being secured to 80 the shirt in the vicinity of the waist-line and adjacent the central portion of the shirt, and at least one plait where the drawers are secured to the shirt, as and for the purposes set forth. 85

4. A combination garment comprising a one-piece suit consisting of shirt and drawers combined, the central portion of the front of the shirt extending downward to the vicinity of the crotch, the drawers being secured to the shirt in the vicinity of the waist line and adjacent the central portion of the shirt, and at least one plait where the drawers are secured to the shirt as and for the purposes set forth. 90

5. A combination garment comprising a one-piece suit consisting of shirt and drawers combined, the central portion of the front of the shirt extending downward to the vicinity of the crotch, the drawers being secured to the shirt, in the vicinity of the waist line and adjacent the central portion of the shirt, at least one plait where the drawers are secured to the shirt and means for retaining said plait in position as and 100 for the purposes set forth. 105

In testimony whereof I have signed this specification in the presence of two subscribing witnesses.

EDWARD J. QUIGLEY.
